UNITED STATES PATENT OFFICE.

MELVILLE CLARK, OF CHICAGO, ILLINOIS.

AUTOMATIC PIANO.

No. 876,438.

Specification of Letters Patent.

Patented Jan. 14, 1908.

Application filed February 8, 1906. Serial No. 300,037.

To all whom it may concern:

Be it known that I, MELVILLE CLARK, a citizen of the United States, residing at Chicago, in the county of Cook and State of Illinois, have invented new and useful Improvements in Automatic Pianos, of which the following is a specification, reference being had to the accompanying drawings, forming a part thereof.

10 The purpose of this invention is to provide in a grand piano automatic playing devices which will not materially affect the proportions of the piano case nor comprise any obtrusive additions to the outlines or appearance of the instrument as a whole, and which 15 may be readily applied with the minimum changes to grand pianos of customary construction and form of case.

It consists of the features of construction 20 and disposition of the several parts set out in the claims.

In the drawings:—Figure 1 is a side-elevation of a grand piano embodying my improvements. Fig. 2 is a bottom plan of the 25 same. Fig. 3 is a fore-and-aft section at the line 3—3 on Fig. 2. Fig. 4 is a partly sectional front elevation of a duct board at the line 4—4 on Fig. 3. Fig. 5 is a vertical fore-and-aft section of the tracker-frame and 30 rolls showing a modified form of construction. Fig. 6 is a detail section of the foundation board at the line 6—6 on Fig. 2.

I employ a pneumatic action of familiar type shown in former patents, comprising the 35 exhaust or rarefied air chamber, 1, containing the primary pneumatics, 2; and upon this air chamber there are mounted motor pneumatics, 3, 3, 3, arranged in a plurality of banks or levels, three being shown in the 40 drawings, communicating with the chamber, 1, and with the outer air by passages and ports controlled by the valves, 4, 4, 4, connected with the primary pneumatics respectively. This construction and the mode of 45 its operation being thoroughly familiar need not be further described. This pneumatic action is mounted on the under side of the case of a grand or square piano in such position that the tracker-pins or fingers 5, 5, 5, 50 of the motor pneumatics, 3, 3, 3, stand in right-and-left line or lines projecting upward through the bottom board or key table, 6, of the piano case. This bottom board is frequently formed in strips slightly separated so 55 as to avoid any closing or buckling which might result from shrinking and swelling of

the wood; and I may take advantage, as in the construction shown, of one of these right-and-left rifts, 8, or intervals between the strips which form the bottom board for admission of the striker pins up through the bottom board, as described, the rifts being selected or made at the position necessary to admit the pins or fingers to the under side of the manual keys, 7, back of their fulcrums, so that an upward stroke of the pins is equivalent to a down stroke of the fingers of the player on the upper exposed portion of the keys. For guiding the tracker pins or fingers, a guide bar, 9, is preferably mounted in 70 the rift or slot, 8, and apertured to afford guide bearings for the tracker pins, as seen in Fig. 3.

The exhaust bellows, 10, is most conveniently and therefore preferably mounted on 75 the under part of the piano frame rearward of the pneumatic action above described; and the pumbers, 11, 11, are likewise located on the under part of the piano frame, and preferably side by side, directly in the rear 80 of the usual position of the piano pedal supporting frame or harp, having their length extending under the narrow rear end portion of the instrument when the form is that of a grand piano, as shown. Both the exhaust bellows and the pumbers are mounted on a foundation board, 12, in which the necessary passages for communication of the pumbers and exhaust bellows are formed, 85 and on which the necessary valves for controlling these passages are mounted, the exhaust bellows being preferably above said board and occupying space between the fore-and-aft timbers of the piano frame. The pumbers are preferably mounted on the 90 under side of said board. The relation and action of the pumbers with respect to the exhaust bellows, and of the passages and valves to both pumbers and exhaust bellows are familiar and need not be further 95 described.

The exhaust chamber, 1, of the pneumatic action may conveniently and preferably be secured rigidly by brackets, 1^x and 1^y, to the same foundation board, so that this foundation board constitutes the substantial connection of the entire pneumatic action with the exhaust bellows and pumbers, and the entire structure comprising pneumatic action and bellows can thus be handled as a unitary 105 structure and secured bodily and detached bodily from the under side of the piano 110

frame, as indicated by bolts, 13, 13, and brackets, 13^a, so securing it.

The tracker-board, 15, controller-sheet-operating rolls, 16 and 17, and any desirable form of motor mechanism (not shown in the drawing) are mounted upon a frame or supporting device which consists of cheeks, 19, 19, rigidly connected by a back-board, 20, and a bottom board, 21, for carrying the various stops (not shown) by which the tempo and expression are regulated. This entire frame is mounted for movement back and forward between a position under the key table and a position at the forward side of the same, so that it may be drawn out from under the table into position for reaching and manipulating the stops and observing the controlling sheet so far as necessary to enable the performer to suitably use the stops. When not in use the entire frame and parts carried thereby may be moved back under the key table so as not to be obtrusively noticed and so as not to obtrude at all beyond the forward line of the piano case. A preferred construction for mounting this frame so as to permit its movement as described comprises a pair of slides, 25, 25, which are hung for sliding in slide-ways, 26, 26, on the under side of the key table, and are rigidly connected by a bar, 27, so as to slide fore and aft as a unitary structure. The tracker-bar frame (carrying the controller-sheet rolls and motor) is connected at opposite ends to the two slides respectively by a pair of parallel links, 28, 28, at each end, so that the entire tracker frame may swing on the links from a position forward of the manual breast of the piano down first a little forward while the links are approaching horizontal position, and then further down rearward as the links swing below horizontal position until the tracker frame is stopped against the forward edges of the slides, 25, the upper edge of the inclosing case of the entire swinging structure being at that position below the level of the under surface of the key table. The slides are then pushed rearward, carrying the tracker frame underneath the key table.

50 For securing the structure comprising the tracker frame case and contents at elevated position in front of the manual breast there are provided hooks, 29, 29, rigid on a rock-shaft, 30, mounted under the tracker frame, the hooks being adapted to engage studs, 31, on the upper links of each pair of links, 28. The tracker board has a rearwardly extended lip portion, 15^a, through the surface of which the tracker ducts open. A duct-board, 32, is mounted on the under side of the key table having its ducts, 33, connected at their rear ends—conveniently by flexible tubes, 34—with the ducts, 4^a, leading to the primary pneumatics respectively. These ducts, 4^a, extend from the pneumatics in the blocks,

2^a, on which the pneumatics respectively are mounted within the chamber, 1, and thence in the bottom, 1^b, of said chamber, which is extended forward as a duct board under the motor pneumatics and is joined at its forward edge to an upwardly-extending front duct board, 1^c, located directly in front of the system of tracker pins, 5, the ducts, 4^a, opening at the upper end of said front duct board for connection with the flexible tubes, 34. In order that the ducts, 34, may pass by the block, 60, from which the pedal-supporting harp or frame, 61, is hung, the ducts, 4^a, are converged in the front duct board, 1^c, into two groups, as seen in Fig. 4, with an interval between the groups corresponding to the space occupied by the block, 60, and in order to be thus converged, the ducts are also arranged in two planes, alternate ducts being in a rear group and alternate ducts in the forward group, as indicated in Fig. 3. The duct board, 32, has its ducts, 33, in three groups, and the ducts, 34, are still further converged from the two groups of the board, 1^a, to the three groups of the duct board, as seen in Fig. 2. The devices and methods shown for converging the ducts from the full right-and-left compass of the primary pneumatic system to the reduced compass of the tracker board is familiar in the art and requires no more particular explanation. The ducts, 33, open at their forward ends through the under surface of the duct board, 32; in position to register with the tracker ducts which open upwardly through the upper surface of such tracker-board lip, 15^a. The hooks, 29, have their faces for engagement with the studs, 31, shaped so as to slightly draw or crowd the entire tracker frame upward to press the lip, 15^a, of the tracker-board closely against the duct-board, 32, the meeting surfaces of the two boards being preferably covered with suitable material, as thin felt, 35, to make the junction air-tight and the registration of the duct mouths effective in rendering each air passage continuous and separate from every other. A spring, 36, coiled about the rock-shaft, 30, reacts to rock the shaft in proper direction for swinging the hooks into engagement with the studs; and the hooks are slope-nosed for encounter with the studs, so that they are crowded back when the tracker frame is lifted and snap into engagement at the highest position of the latter. A thumb-lever, 37, on the rock-shaft serves to release the hooks when the frame is to be lowered and swung back out of use.

The pumpers may be operated by any convenient mechanical connections with pedals, 50, 50, as, for example, by a cable, 38, extending from each pedal over a guide pulley, 39, mounted on a bracket arm, 40, rigid with the cross bar, 27, which connects the slides, 25; thence rearward for connection with one

arm, 41, of a bell-crank lever whose other arm, 42, is suitably connected to the moving member of the pumper bellows.

When the tracker board is to be mounted 5 for adjustment transversely of the controlling sheet, as for transposition or correction of alinement of the ducts with the perforations of such sheet, the construction may be modified, as shown in Fig. 5, by interposing 10 between the adjustable tracker board, 15^a, and a rear duct board, 15^b, which corresponds to the rear extension, 15^a, of the tracker board in the form shown in Fig. 2, 15 flexible tubes, 15^y, connecting the corresponding ducts of the adjustable tracker board and said duct board, 15^b.

I claim:

1. In an automatic square or grand piano, in combination with the piano frame, a 20 foundation board mounted on the under side of the frame; an exhaust bellows, pumper bellows and a pneumatic action all mounted on the foundation board, said board together with said parts mounted thereon being 25 adapted to be detachably secured as a unitary structure to the piano.

2. In an automatic square or grand piano, in combination with the piano frame, an automatic operating mechanism comprising 30 an exhaust air chamber and exhausting devices; a pneumatic action comprising primary and motor pneumatics, said exhaust air chamber and exhausting devices and pneumatic action being detachably mounted upon the 35 under side of the piano frame; a duct board detachably secured to the under side of the key table and means connecting its ducts respectively with the primary pneumatics, in combination with a tracker-board frame and 40 music and take-up rolls and operating mechanism mounted thereon, the tracker board having its ducts adapted to register with the ducts of the duct board, and means for supporting 45 said tracker frame for movement from such registering position rearward to a position underneath the key table.

3. In an automatic square or grand piano, in combination with the piano frame, an automatic operating mechanism consisting 50 of a foundation board; an exhaust air chamber and exhausting devices mounted on said board; a primary pneumatic chamber and motor pneumatics mounted thereon exterior to said chamber, being also secured to the 55 foundation board, whereby the parts described may be detachably secured as a unitary structure to the under side of the piano frame; a duct-board detachably secured to the under side of the key table, and means 60 connecting its ducts respectively with the primary pneumatics, in combination with a tracker-board frame and music and take-up rolls, and operating mechanism mounted thereon, the tracker-board having its ducts 65 adapted to register with the ducts of the

duct-board, and means for supporting said tracker frame for movement from such registering position rearward to a position underneath the key table.

4. In an automatic square or grand piano, 70 in combination with the piano frame, a foundation board, pumbers, an exhaust bellows and an exhaust air chamber mounted on said board, the latter having ducts for communication of the pumbers with the exhaust bellows, and of the exhaust bellows with the exhaust air chamber; motor pneumatics mounted on the exhaust air chamber in position for collapsing by upward movement of their moving walls, the piano frame 80 being apertured in line transverse to the manual keys under the rear ends of said keys, and tracker pins or strikers connected with the motor pneumatics, respectively, operating upward through such apertured frame upon 85 the manual keys rearward of their fulcrums.

5. In an automatic square or grand piano, in combination with the piano frame, key-actuating mechanism mounted upon the under side of the rear part of said frame comprising tracker pins or strikers for operating upward against the under side of the manual keys and pneumatic operating mechanism therefor; a tracker-board, music and take-up rolls and operating mechanism and a rigid 95 frame in which said parts are mounted; a duct board detachably mounted on the under side of the forward part of the piano frame, and connections from such duct board to the pneumatic operating mechanism, the said rigid frame being mounted on the piano frame 100 for movement from a position forward of the manual breast of the piano to a position underneath the key table, the tracker board having its ducts registering with those of the 105 duct board at said forward position.

6. In an automatic grand or square piano, in combination with the piano frame a rigid frame comprising a tracker board; music and take-up rolls and operating mechanism 110 mounted on such frame; fore-and-aft slides on the under side of the piano frame, and slides mounted for movement fore and aft therein; a pair of links connecting each of said slides with said rigid frame for movement of said frame relatively to the slides in a vertical fore-and-aft curved path; and means for locking the rigid frame at the upper limit of such path.

7. In an automatic grand piano, in combination with the pedal-supporting harp and piano frame, automatic playing devices mounted on the frame comprising a foundation board secured to the under side of the frame rearward of the pedal-supporting harp, 120 the exhaust bellows being mounted upon the upper side of such foundation board between the frame timbers, and the pumbers being mounted on the under side of said foundation board.

130

8. In an automatic piano, in combination with the piano frame, a foundation board mounted on the under side of said frame at the rear part, an exhaust bellows mounted 5 upon the upper side of said foundation board in position for entering between the timbers of the piano frame; pumbers also mounted on said foundation board, and a pneumatic action comprising an exhaust chamber rigidly 10 joined to said foundation board, said board having ducts for communication of the exhaust bellows with the pumbers and with said exhaust chamber.
9. In an automatic grand piano, in combination with the piano frame and pedal support or harp and key table, a pneumatic action mounted upon the under side of such frame comprising motor pneumatics collapsing by upward movement of their moving walls, 15 and tracker pins or plungers connected with said moving walls for operating upon the key, such tracker pins extending upward for encounter with the manual keys under the rear ends of the latter; an exhaust air chamber 20 on which the motor pneumatics are mounted; primary pneumatics within such chamber; duct boards having their ducts communicating successively, the first under the primary pneumatic chamber having its duct communicating with the primary pneumatics respectively, the second in front of the motor pneumatics and their tracker pins and the third mounted under the key table, and a tracker board mounted for registration of its 25 ducts with the forward end of the ducts in the last-mentioned duct board.
10. In an automatic grand piano, in combination with the piano frame and pedal support or harp, a pneumatic action mounted 30 under the frame comprising an exhaust chamber; primary pneumatics therein; motor pneumatics mounted on the forward side of said chamber; tracker pins operated by the motor pneumatics respectively extending upward for encounter with the under side of the 35 manual keys respectively, such tracker pins occupying a line transverse with respect to the manual keys back of the piano-pedal support or harp; duct boards having their corresponding ducts communicating successively with each other, the first mounted at 40 the under side of the exhaust chamber and having its ducts communicating with the primary pneumatics respectively, the second mounted in front of the line of the tracker pins back of the harp, the third mounted 45 under the key table forward of the harp, and a tracker board mounted for registration of its ducts with the forward end of the ducts of the last-mentioned duct board. The ducts of the second-mentioned duct board being converged from their lower ends in two groups toward the upper ends with an interval between the groups corresponding to the position occupied by the harp, and means for connecting the ducts of the third duct board 50 with those of the second.
11. In an automatic grand piano, in combination with the piano frame and pedal support or harp, a pneumatic action mounted under the frame comprising an exhaust chamber; primary pneumatics therein; motor pneumatics mounted on the forward side of said chamber; tracker pins operated by the motor pneumatics respectively extending upward for encounter with the under side of the manual keys respectively, such tracker pins occupying a line transverse with respect to the manual keys back of the piano-pedal support or harp; duct boards having their corresponding ducts communicating successively with each other, the first mounted at 55 the under side of the exhaust chamber and having its ducts communicating with the primary pneumatics respectively, the second mounted in front of the line of the tracker pins back of the harp, the third mounted under the key table forward of the harp, and a tracker board mounted for registration of its ducts with the forward end of the ducts of the last-mentioned duct board. The ducts of the second-mentioned duct board being converged from their lower ends in two groups toward the upper ends with an interval between the groups corresponding to the position occupied by the harp, and means for connecting the ducts of the third duct board 60 with those of the second.
12. In an automatic grand piano, in combination with the piano frame and pedal support or harp, a pneumatic action mounted under the frame comprising an exhaust chamber; primary pneumatics therein; motor pneumatics mounted on the forward side of said chamber; tracker pins operated by the motor pneumatics respectively extending upward for encounter with the under side of the manual keys respectively, such tracker pins occupying a line transverse with respect to the manual keys back of the piano-pedal support or harp; duct boards having their corresponding ducts communicating successively with each other, the first mounted at 65 the under side of the exhaust chamber and having its ducts communicating with the primary pneumatics respectively, the second mounted in front of the line of the tracker pins back of the harp, the third mounted under the key table forward of the harp, and a tracker board mounted for registration of its ducts with the forward end of the ducts of the last-mentioned duct board. The ducts of the second-mentioned duct board being converged from their lower ends in two groups toward the upper ends with an interval between the groups corresponding to the position occupied by the harp, and means for connecting the ducts of the third duct board 70 with those of the second.
13. In an automatic grand piano, in combination with the piano frame and pedal support or harp, a pneumatic action mounted under the frame comprising an exhaust chamber; primary pneumatics therein; motor pneumatics mounted on the forward side of said chamber; tracker pins operated by the motor pneumatics respectively extending upward for encounter with the under side of the manual keys respectively, such tracker pins occupying a line transverse with respect to the manual keys back of the piano-pedal support or harp; duct boards having their corresponding ducts communicating successively with each other, the first mounted at 75 the under side of the exhaust chamber and having its ducts communicating with the primary pneumatics respectively, the second mounted in front of the line of the tracker pins back of the harp, the third mounted under the key table forward of the harp, and a tracker board mounted for registration of its ducts with the forward end of the ducts of the last-mentioned duct board. The ducts of the second-mentioned duct board being converged from their lower ends in two groups toward the upper ends with an interval between the groups corresponding to the position occupied by the harp, and means for connecting the ducts of the third duct board 80 with those of the second.
14. In an automatic grand piano, in combination with the piano frame and pedal support or harp, a pneumatic action mounted under the frame comprising an exhaust chamber; primary pneumatics therein; motor pneumatics mounted on the forward side of said chamber; tracker pins operated by the motor pneumatics respectively extending upward for encounter with the under side of the manual keys respectively, such tracker pins occupying a line transverse with respect to the manual keys back of the piano-pedal support or harp; duct boards having their corresponding ducts communicating successively with each other, the first mounted at 85 the under side of the exhaust chamber and having its ducts communicating with the primary pneumatics respectively, the second mounted in front of the line of the tracker pins back of the harp, the third mounted under the key table forward of the harp, and a tracker board mounted for registration of its ducts with the forward end of the ducts of the last-mentioned duct board. The ducts of the second-mentioned duct board being converged from their lower ends in two groups toward the upper ends with an interval between the groups corresponding to the position occupied by the harp, and means for connecting the ducts of the third duct board 90 with those of the second.
15. In an automatic grand piano, in combination with the piano frame and pedal support or harp, a pneumatic action mounted under the frame comprising an exhaust chamber; primary pneumatics therein; motor pneumatics mounted on the forward side of said chamber; tracker pins operated by the motor pneumatics respectively extending upward for encounter with the under side of the manual keys respectively, such tracker pins occupying a line transverse with respect to the manual keys back of the piano-pedal support or harp; duct boards having their corresponding ducts communicating successively with each other, the first mounted at 95 the under side of the exhaust chamber and having its ducts communicating with the primary pneumatics respectively, the second mounted in front of the line of the tracker pins back of the harp, the third mounted under the key table forward of the harp, and a tracker board mounted for registration of its ducts with the forward end of the ducts of the last-mentioned duct board. The ducts of the second-mentioned duct board being converged from their lower ends in two groups toward the upper ends with an interval between the groups corresponding to the position occupied by the harp, and means for connecting the ducts of the third duct board with those of the second.

In testimony whereof, I have hereunto set my hand, in the presence of two witnesses, at Chicago, Illinois, this 3d day of February, A. D., 1906.

MELVILLE CLARK.
